UNITED STATES PATENT OFFICE.

JOHN SMITH, OF BURTON-ON-TRENT, ENGLAND.

BUNG-WRENCH.

SPECIFICATION forming part of Letters Patent No. 450,381, dated April 14, 1891.

Application filed August 6, 1889. Renewed July 10, 1890, Serial No. 358,267. (No model.) Patented in England July 22, 1889, No. 11,672, and in Germany July 31, 1889, No. 52,499.

To all whom it may concern:

Be it known that I, JOHN SMITH, a subject of the Queen of Great Britain, residing at Elms Road, Burton-on-Trent, in the county 5 of Stafford, England, have invented new and useful Improvements in Apparatus for Withdrawing Bungs or Shives from Casks, (for which I have obtained a patent in Great Britain, No. 11,672, bearing date July 22, 1889, 10 and in Germany, No. 52,499, bearing date July 31, 1889,) of which the following is a specification.

The object of this invention is to facilitate the withdrawal of barrel bungs or shives 15 without injury to the staves or bung-bushes of the casks.

In the accompanying drawings, Figure 1 represents longitudinal section of an apparatus for withdrawing bungs or shives from 20 casks constructed according to my invention. Fig. 2 represents side elevation of same. Fig. 3 represents plan of same. Fig. 4 represents extractor detached from the apparatus.

According to this invention the apparatus 25 consists of an approximately circular portion *a* to encircle the bung or shive. On one side of the portion *a* is a projecting piece *b*, forming a bearing, on which works a cam-lever *c*. On the opposite side of the portion *a* is a divided handle *d*, having a lever *e* pivoted to 30 the end thereof at *f*. This lever carries the extractor *g*, consisting of the knife *h*, connected by the circular portion *i* to a square or other suitably-shaped neck *j*, which neck 35 terminates in a head *k*. The lever *e* has pivoted to it at *l* the cam-lever *c*. When the extractor *g* is inserted in the lever *e*, a loose

piece *m* is inserted to fill up the superfluous space and kept in position by any suitable means, such as a pin *n*, a spring *o* serving to 40 keep the extractor pressed against the portion *p* of the lever *e*.

To withdraw a shive or bung from a cask, the apparatus is placed over the shive, the extractor *g* driven through the shive in the 45 direction of the grain, the apparatus turned about a quarter of revolution on the circular portion *i* of the extractor *g* as a pivot, and the cam-lever *c* struck down in the direction of the arrow by the mallet or other implement with which the extractor *g* is driven. The shive will thus be extracted without the workman having to change or lay down his tools.

I would remark in conclusion that I do not 55 limit myself to the precise details of the apparatus or knife shown in the drawings.

What I claim as my invention, and desire to secure by Letters Patent, is—

In an apparatus for withdrawing bungs or 60 shives from casks, the combination of the approximately circular portion *a*, having at one side a projection *b* and having at its opposite side a projection *d*, to which is pivoted the lever *e*, through which lever passes the extractor *g*, with the cam-lever *c* pivoted to the lever *e* and bearing upon the projection *b*, all 65 substantially as described.

JOHN SMITH.
